AUTOMATIC HEAT-TREATING MACHINE

David M. Strauchen and Milton Garvin, Cincinnati, Ohio, assignors to The Cincinnati Milling Machine Co., Cincinnati, Ohio, a corporation of Ohio

Application August 28, 1945, Serial No. 613,090

7 Claims. (Cl. 266—4)

1

This invention relates to heat treating apparatus and more particularly to improvements directed toward producing an apparatus or machine for heat treating purposes which is entirely automatic in operation. One of the reasons for heat treating metallic articles is for prevention against wear, and since this can be accomplished by simply hardening a thin layer of the outside material of the article to be treated a method known as flame hardening is utilized because of its efficiency in that an intense heating effect can be produced at the necessary surface areas without heating the entire article. From a metallurgical standpoint, however, these heating operations are very critical, there being a correct temperature and time of quench for each of the various metals and alloys, departure from which results in an inferior product.

It has been found that even duplicate parts composed of the same material may take slightly different lengths of time to arrive at the same quenching heat. Thus, a number of variables, some predictable and some not, enter into such a heat treating operation. Heat treating machines of the past have required skilled operators and, even then, exact results have not been obtained. Take, for instance, in the measuring of heat, some use a time control on the assumption that similar articles will heat in exactly the same time—which has been found to be untrue—while others use an electric eye apparatus for cutting off the heat, but such apparatus is not sensitive throughout the heating cycle and variations in temperature are not noted.

This invention obviates these difficulties, and one of the objects of this invention is to provide a complete automatic machine for heat treating purposes in which the variable factors are automatically compensated for in such a manner that not only is each work piece heated to exactly the same temperature regardless of the time it takes to heat it, but the quench is applied at the proper interval of time after heating, and all in such a quick and efficient manner that very high production rates can be obtained and the machine may be operated by unskilled operators whose only duty is to load and start the machine.

Another object of this invention is to provide a machine for the purposes described which is compact, durable, efficient in operation, and economical to build.

A further object of this invention is to provide a new and improved automatic control mechanism for a machine of the character described which may be preset to the desired

quenching temperature and which will automatically, upon attainment of that temperature by the work, shut down the machine, extinguish the heat, quench the work and place the machine in readiness to receive a new work piece.

A still further object of this invention is to provide an improved automatic heat treating machine which is especially suitable for heat treating the surfaces of circular work pieces such as gears, cams, and the like, which are ordinarily difficult to uniformly heat by providing automatic and sequential controls for starting rotation of the work, applying the heat, and when the work has reached the desired temperature, shutting off the heat, stopping the work rotation, ejecting and quenching the work.

Another object of this invention is to provide a machine of the character described which is automatic in operation and suitable to be placed in a high production manufacturing or assembly line for heat treating mechanical parts which are used in large quantities in highly mechanized production plants, such as for heating gears in a supply line for gear box assemblies in automobile manufacturing plants.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a front elevation of a machine embodying the principles of this invention.

Figure 2 is a side view, as viewed from the left, of the machine shown in Figure 1 with certain parts broken away to show the work supporting and ejecting mechanism.

Figure 3 is an enlarged fragmentary portion of one of the torch supporting brackets.

Figure 4 is a detail section on the line 4—4 of Figure 3.

Figure 5 is a section on the line 5—5 of Figure 2.

Figure 6 is a view on the line 6—6 of Figure 2.

Figure 7 is an enlarged end view of one of the burners.

Figure 8 is a section on the line 8—8 of Figure 3.

2

Figure 9 is a modified form of the machine shown in Figure 1.

Figure 10 is a section on the line 10—10 of Figure 9.

Figure 11 is a diagram of the control circuit for the machine.

Figure 12 is an elevational view of a modified form of torchhead.

Figure 13 is a sectional view as viewed on the line 13—13 of Figure 12.

Figure 14 is a diagrammatic view of a control circuit for sequential operation of the gas valves.

One embodiment of a machine exemplifying the principles of this invention is shown in Figures 1 and 2 in which the reference numeral 10 indicates the bed of the machine, and from the back of this bed there upstands a column portion 11.

This machine is designed for handling rotary work and to that end the machine is provided with a work supporting spindle 12 which is supported in bearings 13 mounted in a housing 14 which is supported on the rear side of the column wall 15. The spindle projects through the column wall and some distance in front of it so that the heating operation of the work supported on the end of the spindle will be spaced some distance from the wall to prevent heating thereof. For further protection, the front of the wall is provided with a layer of asbestos material 16 to prevent the passage of heat through the wall to the instrumentalities located behind the wall.

The spindle 12 is provided with a removable arbor 17 so that different size arbors may be substituted therefor, whereby an arbor may be chosen that has a diameter equal to the diameter of the hole in the work piece to be treated to the end that a good sliding fit may be obtained. The arbor is provided with a key to fit the keyway in the work piece and thereby form a driving means for rotation of the work. It has been found that if a good sliding fit between the work and arbor is obtained that it is not necessary to provide any retainer for the work on the end of the arbor such as a nut or the like to hold the work on during rotation, and this simplifies the operation of the machine because the operator simply has to place the work on the arbor and an automatic ejecting means can slide the work off at any time.

In the cases of work pieces that have no central bore but have a projecting stud the removable arbor may be made in the form of a chuck for receiving the stud.

The spindle 12 is provided with a sprocket wheel 18 through which it is driven by a variable speed motor 19 connected thereto through a sprocket wheel 20 and driving chain 21. The motor is preferably of the gear reduction type and the drive from the pulley 20 to the pulley 18 is also a reducing drive so that the work piece represented by the reference numeral 22 may be rotated at a relatively slow speed around 80 to 100 revolutions per minute. The speed of work revolution is varied in accordance with the diameter of the work in such a manner as to give a constant peripheral speed past the heating burners, and it has been found that a peripheral speed of 100 R. P. M. gives the most satisfactory rate of heating. In order to effect variations in the ultimate speed of the work, a rheostat or other speed controlling unit 23 is placed in the control circuit for the motor as more particularly shown in Figure 4.

The work is heated by rotating the same in the center of a heating zone developed by placing a series of burners or tips around the periphery of the work, the number and position of which will

vary in accordance with the size of the work and the configuration of its outer surface. For illustration purposes there has been shown two torches 24 and 25 which are supported on opposite sides of the work, and each torch is provided with a series of tips or burners 26. The face 27 of the torch head is provided with two or three rows of threaded holes in which the burners or tips are attached as shown in Figure 7. It is usually not necessary to use all of these holes and so the remainder are closed by threaded plugs as indicated at 28.

The tips or burners 26 are made of different length as shown in Figure 1 of the drawings so that the end of each tip is substantially the same distance from the periphery of the work, and this makes it possible to place the highest temperature zone of the flame in proper relation to the surface to be heated. It will be noted that the burners all extend in parallel relation rather than in radial relation with respect to the center of rotation of the work and the advantage of this is that in cases where the work has indentations therein that the flame from the burner on one side of the center of rotation will obtain good contact with one wall of the indentation and the flame from the burners on the lower side of center will obtain a good contact with the other wall of the indentation, thereby obtaining a more uniform manner of heating action.

For the purposes of adjustment and set-up and to take care of variations in the size of work and the manner in which it is to be heated, the torchheads are supported on the top of the bed 10 for variable adjustment. The adjustable support for each head is the same. For instance the torchhead 24 which is rectangular in cross section is mounted in a rectangular slot 29 of an angularly adjustable bracket 30. The torchhead is secured in the slot by a pair of screws 31 as shown in Figure 8. The bracket has a circular flange 32 which is rectangular in cross section and fits into a rectangular slot 33 formed in the upper end of an upright or standard 34 as shown in Figure 3. The flange 32 is provided with a circular slot 35 and through this slot passes a clamping screw 36 which is threaded at one end 37 into the upright 34 for frictionally clamping the flange in the upright in whatever angular position it is desired to place the torchhead. The periphery of the flange 32 is graduated at 32a for cooperation with a fixed reference mark 32b on the upright 34 so that a given setting of the torchhead may be reproduced for a given style of work piece and also that the opposite torchhead may be similarly adjusted. It is often necessary, however, to give the opposite torchheads an opposite angle of adjustment, as for instance when treating helical gears, because the teeth on one side of the gear are, of course, opposite in angle to the teeth on the other side; therefore, the torchheads have to be angularly adjusted in accordance therewith.

The uprights 34 are secured to the end of blocks 38 by a screw 39 which passes through a slotted hole 40 in the member 34 to permit vertical adjustment thereof. The blocks 38 are fastened by screws 41 to longitudinally adjustable slides 42 which slide on top of T-slotted plates 43 secured to the bed 10. T-headed bolts 44, as shown in Figure 4, mounted in the T-slotted member 43 pass through the plate 42 for the purpose of clamping the same. The plate 42 is provided with graduations 45 which cooperate with a zero mark 46 to determine the location of the parts and for purposes of reproducing the position.

Similarly, the upright 34 has graduations 47 which cooperate with a zero mark 48 to give location of the parts and permit reproducing the setting. It will now be apparent that the torch-heads may be adjusted toward and from one another and may also be vertically adjusted as well as angularly adjusted.

The torches are provided with a mixture of oxygen and acetylene gas through a supply pipe 47' which is connected by means of an elbow 49' to the rear of the torch head. As shown in Figure 11, the supply pipe 47' is connected to a mixing chamber 49 and this chamber has two inlets 50 and 51, the inlet 50 supplying the oxygen and the inlet 51 supplying the acetylene. Individual control valve knobs 52 and 53 determine the mixture of gases in the chamber 49 and the mixed gas then flows through the pipe 47' to the burners. The inlet 50 is connected by a pipe 54 to a shut-off valve 55 and the inlet 51 is connected by a pipe 56 to a shut-off valve 57. It will be noted from Figure 11 that duplicate control systems are provided for each burner, and duplicate shut-off valves 55 for the oxygen, and duplicate shut-off valves 57 for the acetylene are provided for each burner.

The shut-off valves 55 have branch connections 58 to a main source of oxygen supply represented by the numeral 59. The shut-off valves 57 are connected by branch connections 60 to a main source of acetylene supply represented by the numeral 61. The shut-off valves 55 and 57 are connected by pins 62 to a solenoid operated lever 63 which is pin-connected at 64 to a bracket 65, formed integral with the valve block 66. Springs 67 interposed between the top of the valve block and the lever 63 act to normally hold the supply valves closed. It will thus be seen that after the mixture for each torchhead has been determined by the valve adjusters 52 and 53 that in normal operation of the machine the shut-off valves are automatically opened to provide a supply of gas and when the operation is completed the supply of gas is shut off.

After the gear has been heated to the correct temperature it is automatically removed from the work supporting spindle by an ejector mechanism. This mechanism comprises a plunger 68 which is slidably mounted in an electric solenoid 70 supported on the rear side of the front wall 15 of the column. A spring 71 is interposed between a shoulder 72 formed on the plunger and a supporting block 73 for normally holding the plunger in a retracted position. As shown in Figure 1 a plate 74 is attached by a bolt 75 to the front end 69 of the plunger 68 and in this plate are threaded secured a pair of ejector fingers 76. These fingers are made of relatively soft metal so that they may be readily bent to suit the shape of the work, thereby eliminating the necessity for providing lateral adjustment of the fingers in the supporting plate. It will now be obvious that when the solenoid 70 is electrically energized that the plunger will move forward and push the work piece off of the spindle. The work piece is given a sufficient kick that it will hit a deflecting plate 77 and fall into the quenching oil in the quenching tank 78 located in the bed 10 of the machine.

In the embodiment of the machine shown in Figures 1 and 2 the quenching tank 78 is made as a separate unit which is adapted to be pulled forward out of the bed of the machine for removal of the work which has been treated. In order to permit easy removal of the work the tank has a pair of rollers 79 secured to each side, and the

bed of the machine is provided with angle iron tracks 80 upon which these rollers move. As shown in Figure 2, the rollers 79 are secured to the rear of the tank to support the weight at the back end, and the front end of the tank is provided with a roller caster 81 to support the weight at the front end of the tank.

The tank is provided with a wire basket 82 which may be lifted out of the tank by hand or by an overhead crane, depending upon the weight of the work. To facilitate removal of the tank the front wall 83 of the tank is provided with hand holes 84 for gripping the handle portions 85.

The temperature of the work is determined directly and accurately by radiation, and this is accomplished by supporting an electric thermopile, represented generally by the reference numeral 86 in Figure 5, which is supported in the upper end of a viewing tube 87. This tube is supported in spaced relation to an outer tube 88 which is pivotally connected on opposite sides at 89 to a bifurcated arm 90. The arm 90 has an axially slidably connection with a bifurcated block 91 which is slidably mounted on an upright standard 92 and adapted to be clamped thereto by a screw 93 passing through the bifurcated portion of the member 91. Standard 92 is mounted on the top of the column 11. By means of these various connections the viewing tube may be adjustably positioned in suitable spaced relation with the periphery of the work to collect the heat radiation from a definite portion of the surface of the work and direct it on the thermopile. In order to prevent the flames from the burning gas from overlapping on the top of the work and thereby interfering with the true radiation of the heat from the work a compressed air supply pipe 94 is threaded connected at 95 to the side of the tube 87 as shown in Figure 5 to provide a gentle downward flow of air through the end of the tube to keep the flame away from the top surface of the work at the point where the heat measurement is made.

As shown in Figure 11 the thermopile is electrically connected by a pair of wires 96 and 97 for operation and movement of a movable indicator 98 of a temperature control instrument 99 of a known commercial type which has a presettable indicator 100. It is sufficient to say at this time that when the movable indicator 98 reaches a position in juxtaposition to the presettable indicator 100 that an electrical control switch 101 is opened within the instrument to cause automatic shutdown of the machine and ejection of the work. In other words, the instrument 99 has a normally closed switch 101 and this switch is connected in series between a power main 102 with a starting switch 103 and a relay 104 to a power main 105.

The manner in which the various operating devices, such as the work driver, the gas control valve, the ejector, the gas igniter and the temperature control mechanism are coupled together to obtain automatic operation of the machine, will now be explained in connection with Figure 11. The control circuit shown in this figure is so designed that a complete automatic cycle may be effected by merely pushing the cycle control start button 103, or alternatively the various operating devices may be controlled separately as for set-up purposes.

The automatic cycle will first be explained and in this cycle the operator loads a work piece on the spindle and presses the start button 103 after which the entire cycle of the machine is automatically controlled so that the operator has

nothing to do until it is time to load another work piece on the machine. The automatic sequence of events in an automatic cycle is as follows: rotation of the work, turning on the gas, and igniting the gas. The work is thus rotating in the heating zone and the temperature of the work begins to rise causing movement of the movable temperature indicator 98. When the temperature as recorded by this indicator reaches the temperature as indicated by the presettable indicator 100 the switch 101 opens causing the gas to be shut off, thereby extinguishing the heating flames, the work stops rotating, and the ejector forces the work piece off of the spindle causing it to be quenched in the quenching tank.

Referring to Figure 11, the operator first closes the main switch 106 to connect current to the power lines 102 and 105 of the circuit shown. The automatic cycle of operation is started by closing the cycle control start switch 103 which energizes the latching in relay 104, thereby causing contacts 104a to complete a latching-in circuit through normally closed stop button 107 around the starting switch 103 so that a circuit is now completed through relay 104, closed contacts 104a, stop button 107, and normally closed instrument switch 101 to power line 102. For automatic cycle of operation, the operator has set the selector switch 108 on contact button 109 so that upon operation of the starting push button 103 the automatic cycle control relay 110 is also energized.

The operation of relay 110 closes contacts 111, thereby completing a circuit through line 112, branch line 113 to starter 114 for the work driving motor 19. This starter relay closes contacts 115 to energize coil 116 and thereby close the circuit through lines 117 and 118 to the motor 19. Line 118 is connected by branch line 119 to the power main 105 and the line 117 is connected through the speed regulator 23 and branch line 120 to power main 102. The result is that the motor 19 starts the rotation of the work.

Operation of the automatic cycle control relay 110 also closes contacts 121 to complete a circuit from power main 105 through line 122 to the gas control relay 123. Operation of this relay closes contacts 124 to complete a circuit from power main 102 to line 125 which is connected in parallel to the gas valve control solenoids 126 and 127. The other side of these solenoids is connected in parallel by line 128 to power main 105. The result of this operation is that the gas valves are open whereby the torches are supplied with gas. The closing of the latching-in relay 104, closes contacts 128' which completes a circuit from power main 105 through line 125', normally closed stop button 126', line 127, and normally closed stop button 128 to the junction point 129. When the relay 123 closed, it closed a pair of contacts 130 completing a circuit from junction point 129 to relay 123, and also closed a pair of contacts 131, closing a circuit from power main 105 to timer relay 132. The relay 123 also closed a pair of contacts 133 in series with a pair of normally closed contacts 134 of timer relay 132, in a circuit between the secondary 137 of a transformer 138 and a primary 139 of a spark coil 140.

The normally closed contacts 134 are controlled by the timer relay 132 which has a timed opening and an instantaneous closing. Therefore, when the contacts 133 closed, a circuit was momentarily established between the transformer 138 and spark coil 140 until the contacts 134 are opened by the timer relay 132. Thereafter the circuit remains open until the machine stops.

At that time the relay 123 releases first to open contacts 131 and 133 and thereby release timer relay 132 which subsequently closes contacts 134 without establishing a new circuit connection but it does condition the circuit for the next cycle of operation.

The primary 141 of the transformer 138 is permanently connected to the lines 119 and 120 which lead to the power mains 105 and 102 respectively. Therefore, closing the intermediate circuit energizes the spark coil 140 and its secondary 142 whereby a spark is created across the spark gap 143 which is located adjacent each of the burners to ignite the gas. The result of the initial operation of the circuit is that the work is being rotated, the gas has been turned on and ignited, and the work begins to heat up.

The thermopile is sensitive to the rising temperature of the work, causing movement of the temperature indicator 98. When the temperature shown by the presettable indicator 100, the instrument switch 101 opens. This breaks the circuit to both of the relays 104 and 110. The deenergization of the automatic cycle relay 110 opens contacts 111, thereby breaking the circuit to the work driving motor control relay 114, thereby breaking the circuit to the motor whereby the work stops rotating. Also, the opening of contacts 124' associated with relay 104 and contacts 121 associated with relay 110 breaks the circuit to relay 123 and timer relay 132. The deenergization of relay 123 opens contacts 124 whereby the solenoids 126 and 127 are deenergized to cause automatic closing of the gas valves.

After the gas has been shut off and the work stops rotating, provision is made for automatically ejecting the work and this brings in the element of the time of quenching. With some materials it is desirable to quench instantly, while with other materials a slight delay is desired before the quenching takes place in order to obtain the best results. Means have been provided for making a selection between these two alternatives, and to this end a selector switch 144 is provided and this switch is directly connected to the power main 102. The operator sets this switch at the time he sets up the machine, and for instantaneous quench he sets the switch on switch button 145. This establishes a circuit through relay 146, line 147, normally open timer relay contacts 148 of a timer relay 149, and normally closed contacts 150 of work motor starter relay 114.

The timer relay 149 is operated simultaneously with the motor controller relay 114 whereby the normally closed contacts 150 are opened and the timer relay contacts 148 are closed. The result is that the contacts 150 open before the contacts 148 close, so that the relay 146 does not become energized when the machine is started. The timer relay 149 is adjusted for a timed opening whereby when the relay contacts 148 open the contacts 150 close immediately but the contacts 148, being slow to open, complete a circuit to energize the relay 146. Energization of relay 146 closes contacts 151, thereby completing a circuit from power main 105 through ejector control relay 152, line 153 and closed contacts 151 to power main 102. When the relay 152 is energized it closes contacts 154 in a circuit from power main 105 to the ejector solenoid 79 and back to line 102. The work is thereby automatically ejected.

When a time delay is desired for ejection the selector switch 144 is placed on the contact button 155 thereby completing a circuit through

line 156 to the timer relay contacts 151. The operation in this case is that the timer relay 158 is operated but being timed closed and instantaneous opened there will be a slight delay before the contacts 151 close and cause operation of relay 152 and thereby operation of the ejector.

Since the relay 152 is a timer relay it will automatically open after the ejection, thereby setting the circuit for the next cycle. It should also be noted that after the burners have been turned off that the movable indicator 98 of the temperature recording instrument 99 will recede, thereby reclosing switch 101 for the next cycle of operation.

It will thus be seen that when the work has reached the proper temperature that the machine is automatically shut down by closing off the gas supply, stopping rotation of the work spindle and ejecting the work for quenching either immediately or with a slight time delay.

If the machine is to be used in a conveyor line for high production work the modified form of machine shown in Figures 9 and 10 is utilized. In this machine when the work is ejected from the work supporting spindle 12 it falls onto a wire conveyor belt 159 which is traveling in the direction of the arrow 160. As shown in Figures 9 and 10 the belt 159 is mounted on an idler pulley 161 which is rotatably supported on studs 162 mounted in and projecting from the opposite walls 163 and 164 of the quenching tank. The sides of the belt are flanged as shown at 165 and these run in a first set of guide pulleys 166 located on the upper side of the belt and a second guide pulley 167 located near the bottom of the tank. The belt also runs over a driving drum 168 which is supported on a shaft 169 that is journaled in the opposite side walls of the tank in bearings 170 and 171.

The shaft 169 has a drive sprocket wheel 172 secured to one end thereof and connected by a drive chain 173 to a sprocket wheel 174 driven by the armature shaft 175 of gear reduction motor 176.

The motor 176, as shown in Figure 11, is connected in series with a start and stop switch 177 between lines 105 and 102. The switch 177 is composed of a pair of contacts forming part of a timer relay 178 which is connected in parallel with the ejection control relay 152 as shown in Figure 11. Therefore, each time the ejection relay 152 is operated to effect removal of a work piece the timer relay 178 is also energized which closes contacts 177 and causes operation of motor 176 causing movement of the conveyor belt 159 in the direction 160. After a predetermined interval of time the timer relay 178 will automatically release, thereby stopping the motor 176. It is thus obvious that the timer relay may be so set that the conveyor belt will travel a predetermined distance to remove the newly fallen work piece a predetermined distance up the incline 179 so that the next piece that falls into the tank will not hit or mar it. Eventually the work piece will move out of the quenching oil whereby the oil starts to drain from the work piece. To facilitate drying the work and removing the excess oil a blower pipe 180 is mounted in the upper part of the bed. This blower pipe is connected to a valve 181. The valve has an inlet 182 which may be connected to a source of compressed air supply represented by the numeral 183 and which supply is normally available in all plants today. The operating control lever 184 of the valve 181 is connected to a solenoid 185 which is also seri-

ally arranged in circuit with a pair of contacts 186 between lines 105 and 102 as shown in Figure 11. The contacts 186 are also part of the timer relay 178 whereby each time the relay is operated and the conveyor moved the blower will be turned on.

After the work reaches the top of the conveyor it is deposited on a slide 187 and may thereby be directed to a shop conveyor system represented generally by the reference numeral 188.

As shown in Figure 9 an incoming shop conveyor system, represented generally by the reference numeral 189, may be provided for depositing work on a work receiving shelf 190 attached to the front of the machine.

The operator thus has only to remove the work from the shelf 190, place it on the work receiving spindle 12 and push the start button 103 for each work piece.

20 It will be obvious that the entire machine may be shut down at any time by pressing the stop button 107.

For individual operation of the work driving motor relay 114 a manually operable switch 191 is placed in series therewith as shown in Figure 11, but in order for this circuit to be effective it is necessary for the operator to press the start button 103 in order to close the relay 124'. At this time the switch 108 will be placed in its 25 manual position in contact with button 193. When the relay 114 is operated in this way by manual operation it will close a pair of contacts 192 forming part of the relay and thereby latch itself in around the start button 191 whereby 30 when the operator wants to stop the motor he actuates the stop button 126'.

Similarly, if the operator wants to manually control the gas control relay 123 there is a manual control start button 194. This is connected

40 in parallel with the contacts 130 of relay 123 whereby actuation with the manual control switch 194 will close the latching-in contacts 130 and maintain the circuit so that in order to close the valves it is necessary for the operator to actuate the stop button 128. A neon light 195

45 is connected in circuit with the relay contacts 124' which is part of relay 104 so that whenever the start button 103 is closed to establish a circuit to the temperature recording instrument a light 195 will be illuminated to indicate that the instrument is connected in the circuit. A second light 196 is connected in series with the normally closed contacts 159 of the work motor control

50 relay 114 whereby whenever this relay is operated to start rotation of the work the light 196 will go out.

Whenever the machine is shut down after completing the heat treating of a particular lot of work pieces with the machine under automatic control, it is desirable to remove whatever work pieces are still in the quenching tank and therefore a separate manual control switch 196' has been provided for the conveyor motor 176, as shown in Figure 11. One side of this switch is connected to the power main 105, and the other side of the switch is connected between the automatic control switch 177 and the motor 176. Thus, the manual control switch may be utilized at any time to effect operation of the conveyor motor at will.

70 It is desirable to prevent excessive heating of the parts, and therefore a water cooling system is provided comprising a control valve 197 to which is connected a suitable source of water supply 198. The valve 197 has branches 199 and

200 leading to the mixing chambers 49 and another branch 201 leading to the cooling tube 88 which surrounds the thermopile. The water returning from the mixing chamber is led through passages 202 and 203 to the torchheads 24 and 25, and after circulating through these heads passes to reservoir through the return pipes 204 and 205.

The compressed air supply represented by the reference numeral 183 may also be connected through the control valve 206 to the supply pipe 94 for supplying the viewing tube 87. A second valve 207 is provided for connecting the supply 10 183 to a pipe 208 which has a series of longitudinally spaced holes therein for creating a wall of circulating air in front of the column wall 15 as shown in Figure 2 for reducing heat radiation from the torchheads against the front wall.

Attention is invited to the fact that only one spark gap 143 is shown for the torches, but it will be understood that a duplicate spark coil may be connected in parallel with the spark coil 140 or dependence may be placed upon one lighted torch lighting the escaping gas from the other torch.

In Figures 12 and 13 there is shown a modified form of burner which may be made in a form and size to suit a particular work piece. This burner provides or creates a more uniform heating zone because it is in a form of an almost continuous ring except for the opening for the heat radiation tube. This form of burner is economical where a long high production run of a particular size of work piece is being treated because it gives more uniform heating throughout the periphery of the work. This burner comprises a circular housing 209 from which radially extends from opposite sides a pair of supporting arms 210. These arms are of the same general shape and size of the supporting portions of the burners previously shown and are adapted to fit into the adjustable brackets 30 which were previously described. In this case the arms 210 are made hollow to form a receiving chamber 211 to which the gas inlet 48 is connected. The gas in this chamber passes through an opening 212 formed in the outer wall of the housing 209 and into an outer chamber 213 which extends all the way around the housing 209. A baffle plate 214 is secured in the housing between end plates 215 and 216, thus dividing the interior of the housing 209 into an exterior chamber 213 and an interior chamber 217. The baffle plate has a series of radial holes 218 formed therein which serve to cause an even distribution and a more uniform pressure of the gas throughout the interior chamber 217. A removable burner plate 219 is attached to the inside of the housing by a series of bolts 220, and this plate carries a series of radial holes 221 through which the gas passes and is ignited on the exterior surface thereof. The object of making the plate 219 removable is that other plates with various patterns and sizes of holes may be substituted to suit the various types of work being treated. By making the plate 219 of the proper material it is not necessary to use special burner tips.

It will be noted that the construction provides a pair of end chambers 222 and 223 through which water may be circulated to keep down the temperature. In order to maintain complete circulation the chamber 223, for instance, may have a water inlet connection at 224 and a water outlet connection at 225 as shown in Figure 12 whereby the water will make a complete circuit around

and through one end of the housing. Similar connections may be provided for the other chamber 222.

It is well known that every time a combined mixture of oxygen and acetylene is ignited or extinguished, there is a minor explosion or at least a loud report. In a high production machine of the type disclosed herein this means a number of these explosions every minute because the gas must be extinguished and lighted for every work piece treated. Since such explosions are somewhat hazardous and also fatiguing to the operator, as well as disturbing to others around the vicinity of such a machine if placed in an open shop, means have been provided for minimizing such explosions to the extent of obtaining a quiet operating machine. This result is obtained by a timing control mechanism which causes the acetylene gas to flow first to the burner 15 and become ignited after which the oxygen gas is added. The opposite effect is obtained when the gas is extinguished—i. e., the oxygen gas is turned off first and then the acetylene gas is turned off.

25 This control mechanism is shown in Figure 14 of the drawings. From this figure it will be seen that separate solenoids have been provided for all of the valves. In other words, the oxygen supply line 59 terminates in a pair of valves 226 and 227 located in the valve blocks 228 and 229 respectively. The valves 226 and 227 correspond to the valve members 55 in Figure 11. The acetylene supply line 61 terminates in control valves 230 and 231 located in the respective valve blocks 228 and 229. The valves 226 and 227 are operated by solenoids 232 and 233, and these solenoids are connected in parallel to conductors 234 and 235, the conductor 234 being connected directly to the power main 165 and the conductor 235 being connected by a switch 236 to the power main 162. Similarly, the valves 230 and 231 are operated by solenoids 237 and 238 which are connected in parallel to conductors 239 and 240, the former being directly connected to power main 165 and the conductor 240 being connected by a switch 241 to the power main 162. There is reproduced in Figure 14 the switch 131 which is controlled from the gas control relay 123 and the timer control relay 132 for the spark control which is the same as that shown in Figure 11. The relay 123 will no longer control the switch 124, but a new control mechanism is now provided for controlling the separate switches 236 and 241. This new control mechanism is still timed for operation from the gas control relay 123 through its operation of the switch 131. Thus, whenever the switch 131 is closed it completes a circuit through a timer relay 242 which is a timer control for delaying the flow of oxygen. At the same time the closing of switch 131 completes a circuit through a relay 243 which carries two sets of switch contacts 244 and 245. The contacts 245 are normally closed, and the contacts 244 are normally open. Thus, when the relay 243 is operated, the contacts 245 open first and then the contacts 244 close which completes a circuit through a relay 246, which relay carries the contacts 244 and thus closes a circuit to the solenoids 237 and 238 causing the acetylene control valves 230 and 231 to open. This produces a flow of acetylene gas to the burners. In the meantime the timer relay 242 which operates on the timed closing and instantaneous opening principle will subsequently cause a switch 247 to close, thereby completing a circuit to re-

lay 248. The relay 248 carries the switch contacts 236 which will now close and cause operation of the solenoids 232 and 233 for the oxygen control valves 226 and 227. Thus, it will be apparent that the acetylene valves will immediately open upon closing of the switch 131 and that the relay 248 will be momentarily delayed by the timer relay 242.

At the same time that the relay 248 was energized a second timer relay 249 connected in parallel therewith was energized and this relay carries the switch contacts 250. This relay operates on the principle of instantaneous closing and timed opening with the result that as soon as the relay 249 is energized the contacts 250 are closed, but since the switch contacts 245 are open no circuit connection is established to the relay 246.

When it is time to shut the gas off the switch 131 will open, causing deenergization of the timer relay 242 which, being set for instantaneous opening, will open the switch 247 and thereby deenergize the relay 248 which, in turn, will open the switch contacts 236 causing the oxygen control valves to immediately close. At the same time the relay 243 will be deenergized, opening switch 244 and closing switch 245. Since the switch 250 has a timed opening the circuit will be maintained through switch 250 and switch 245 to the relay 246 which controls the acetylene so that this relay will not be deenergized until the timed opening of switch 250 which will be subsequent to the closing of the oxygen control valves. Thus, the switch contacts 241 for the acetylene control valve solenoids will be delayed in opening until after the oxygen has been shut off. With this control arrangement the igniting and extinguishing of the burners may be carried out in a quiet manner.

There has thus been provided an improved heat treating machine which is capable of continuous automatic operation in which the only duty of the operator is to load the machine.

1. In a heat treating machine, the combination of a bed, a column upstanding from one side of the bed, a power rotatable spindle journaled in the column for rotating a work piece in spaced relation to the top of said bed, power operable means for firing a heat treating zone around the work carried by said spindle to heat the work to a predetermined temperature, a heating cycle starting and control circuit for said power operable means, means for energizing said circuit to cause said power operable means to initiate a heating cycle, power operable means for ejecting work from the spindle, temperature control means adjusted to respond to the heat of the work when equal to said predetermined temperature and operatively connected to deenergize said circuit and to effect activation of said power operable ejecting means to eject work from said spindle, a quench tank located in the bed below said spindle containing a quenching medium for quenching the work, a power operable work conveying belt located in said medium for receiving the ejected work, and means responsive to each deenergization of said circuit to momentarily energize said last-named power operable means.

2. In a heat treating machine, the combination of a bed, a column upstanding from one side of the bed, a power rotatable spindle journaled in the column for rotating a work piece in spaced relation to the top of said bed, power operable means for firing a heat treating zone around the work carried by said spindle to heat the work to a predetermined temperature, a heating cycle

starting and control circuit for said power operable means, means for energizing said circuit to cause said power operable means to initiate a heating cycle, power operable means for ejecting work from the spindle, temperature control means adjusted to respond to the heat of the work when equal to said predetermined temperature and operatively connected to deenergize said circuit and to effect activation of said power

5 work from the spindle, temperature control means adjusted to respond to the heat of the work when equal to said predetermined temperature and operatively connected to deenergize said circuit and to effect activation of said power

10 operable ejecting means to eject work from said spindle, a quench tank located in the bed below said spindle containing a quenching medium for quenching the work, a power operable work conveying belt located in said medium for receiving the ejected work, and means responsive to each deenergization of said circuit to momentarily energize said last-named power operable means, said belt having an upwardly inclined portion for removing work from said medium, power oper-

15 able means associated with said portion for emitting a blast of air on the passing work, and means responsive to each deenergization of said circuit to effect momentary energization of said last-named power operable means.

20 3. In an automatic machine for heat treating work to a predetermined temperature regardless of time, the combination with power operable means for rotating a work piece, of power operable means for creating and firing a heating zone around the work piece for heating the periphery thereof, a heating cycle starting and control circuit having a starting control relay operatively connected to said power operable means, switch means in said circuit for energizing said relay

25 to effect automatic operation of said power operable means to start the heating cycle, a temperature control instrumentality having a presettable temperature indicator and a movable indicator, an electric thermopile mounted on the machine

30 adjacent said zone for response to work heat radiation, said thermopile being electrically connected for actuation of said movable indicator for progressive movement thereof in accordance with increase in heat radiation on the thermopile,

35 a normally closed switch in said circuit for maintaining energization thereof established by said switch means, said normally closed switch being adapted to be opened in response to juxtaposition of said indicators to break said circuit and stop the heating cycle.

4. In an automatic heat treating machine having a bed and, a column upstanding from the bed supporting a work receiving spindle, the combination of electrically operable means carried by the column for rotating said spindle, electrically operable means for firing a heating zone around said spindle, a heating cycle starting and control circuit including relays for energizing the respective electrically operable means, switch means for energizing said circuit to effect operation of said relays to start the heating cycle, electrically operable means for ejecting work from said spindle, a temperature control mechanism including a thermopile mounted adjacent said work support for

45 response to direct heat radiation from the work, a movable indicator operatively connected to said thermopile for movement in response to increase in heat radiation from the work on the thermopile, a temperature selector indicator presettable

50 in advance of said movable indicator to a predetermined temperature, a control switch in said circuit for maintaining energization thereof established by said switch means, said control switch being responsive to movement into juxtaposition of said indicators to deenergize said cir-

cuit to stop the heating cycle, a quench tank and timing means in said circuit responsive to deenergization thereof to effect a timed energization of said electrically operable ejecting means to eject the work from said spindle into said quench tank, whereby the spindle may be loaded with another work piece during quenching of the heated work piece.

5. A flame hardening machine for automatically heating and quenching a work piece to a prescribed temperature comprising a work support, power operable means for firing a heating zone around the work support to effect heating of the work, a heating cycle starting and control circuit for said power operable means including switch means for energizing said circuit to create automatically said heating zone, a temperature control mechanism for determining the temperature to which the work is to be heated and quenched including a temperature selector presettable to said prescribed temperature, a control switch in said circuit having a normal position for maintaining energization of said circuit established by said switch means, a thermopile positioned adjacent said work for instantaneous response to heat radiation from the work, means electrically connected to said thermopile for progressive movement in response to instantaneous reactions on said electrical connections by said thermopile induced by increase in heat radiation on the thermopile and being movable into juxtaposition with said selector to effect operation of said control switch to deenergize said power operable means to stop the heating cycle at said prescribed temperature, a quenching medium, and means automatically responsive to deenergization of said circuit to eject the work from the work support into said quenching medium to effect immediate quenching of the work at said prescribed temperature.

6. In an automatic heat treating machine, the combination of a rotatable spindle, power operable means for firing a heating zone around said spindle, additional power operable means for rotating said spindle, a heating cycle starting and control circuit for said power operable means including switch means for energizing said circuit to initiate operation of said power operable means, means presettable to the final temperature of the work including a control switch operatively connected in said circuit to maintain energization thereof established by said switch means, a thermopile positioned adjacent said spindle for response to work heat radiation, work temperature indicating means including a movable element electrically connected to said thermopile for progressive movement in accordance with increase of heat radiation on said thermopile, said element being adapted to cause actuation of said

control switch when moved into juxtaposition with the presettable means to deenergize said control circuit and thereby extinguish said heating zone and stop work rotation, and means responsive to deenergization of said control circuit to discharge work from said spindle.

7. In an automatic heat treating machine, the combination of a rotatable work spindle, power operable means for firing a heating zone around said spindle, a heating cycle starting and control circuit for said power operable means including switch means for energizing said circuit to initiate operation of said power operable means, means presettable to the final temperature of the work including a control switch operatively connected in said circuit to maintain energization thereof established by said switch means, a thermopile positioned adjacent said spindle for response to work heat radiation, work temperature indicating means including a movable element electrically connected to said thermopile for progressive movement in accordance with increase in heat radiation on said thermopile, said element being adapted to cause actuation of said control switch when moved into juxtaposition with the presettable means to deenergize said control circuit, a quench tank located below the work spindle, and means responsive to deenergization of said circuit to automatically discharge work from said spindle into said tank.
